UNITED STATES PATENT OFFICE.

ALLEN CROSS AND EVERET F. DUNCAN, OF MUSCATINE, IOWA.

SEWER-ROD OPERATING MECHANISM.

Application filed July 11, 1924. Serial No. 725,466.

To all whom it may concern:

Be it known that we, ALLEN CROSS and EVERET F. DUNCAN, citizens of the United States, residing at Muscatine, in the county of Muscatine and State of Iowa, have invented new and useful Improvements in Sewer-Rod-Operating Mechanism, of which the following is a specification.

This invention relates to sewer cleaning 10 apparatus:

The primary object is to provide a mechanism by which a sewer rod can be operated by lever power from within a manhole.

Another object is to provide a device in 15 the nature of an obstruction remover provided with a system of levers whereby multiplied power can be transmitted to the means contacting the obstruction.

A still further object is to provide a 20 device which includes an adjustable gripping means.

This invention also consists in certain other features of construction and in the combination and arrangement of the several 25 parts, to be hereinafter fully described, illustrated in the accompanying drawings and specifically pointed out in the appended claims.

In describing our invention in detail, reference will be had to the accompanying 30 drawings wherein like characters denote like or corresponding parts throughout the several views, and in which:—

In the drawings:—

Figure 1 is a vertical sectional view taken 35 through a manhole and sewer pipe respectively to illustrate the invention in operative position.

Figure 2 is a sectional view taken on line 40 2—2 of Figure 1.

Figure 3 is a sectional view taken on line 45 3—3 of Figure 2.

Referring to the drawings in detail, A indicates a surface of the ground, B a manhole, C a sewer pipe and D foreign matter 50 representing an obstruction in a section of the sewer pipe.

Arranged within the manhole B and the obstructed section of the sewer pipe C, there 55 is a device which forms the subject matter of the present invention.

A handle 1 is formed on the upper end of the hand lever 2. The hand lever 2 is pivotally secured adjacent its end remote 55 from the handle to one section of an adjustable cross bar 3 whose sections are each pro-

vided with a head 4 arranged on the outer ends thereof for engaging the side walls of the manhole upon diametrically opposite sides thereof, to substantially brace and to provide an adequate fulcrum for the hand lever 2. Openings 5 are formed in the associated ends of the respective sections of the cross bar and these openings receive a bolt and nut securing means 6, whereby the length of the cross bar may be adjusted to conform to manholes of various diameters.

Pivots secured to the lower end of the hand lever 2 there is one end of the link 7 which has its opposite end twisted at right angles upon itself and bifurcated as at 8 to pivotally receive the apex or upper end of a substantially V-shaped cam operating member 9 provided with an arcuate shaped base 10 which has formed therein a channel 75 shaped groove 11. The cam operating member 9 is pivoted adjacent its central portion between the side walls 12 of a substantially U-shaped member 13 which slidably receives the rod portion of a ramming element 14. The ramming element 14 is provided with a head 15 adapted to contact the obstruction D as shown.

The cam operating member 9 engages the rod of the ramming element, the rod being received in the channel shaped groove thereof in a manner whereby a contacting engagement is provided to move the rod. A link 16 has formed thereon adjacent one end a slot 17 which receives a stud 18 projecting from one side wall of the substantially U-shaped member 13. The opposite end of the link 16 is provided with a pair of recesses 19 to alternatively receive a stud 20 projecting from the link 7. By adjusting the link 16 through the medium of the recesses, the gripping action of the cam operating member 9 will be reversed, so that the ramming element can be adequately moved in the direction intended. The ramming element can be released also by movement of the hand lever 2 and such movement will be in the opposite direction from the movement providing the gripping engagement between the respective elements, as above set forth, this movement depending of course upon the position of the link 16.

It is thought from the foregoing description that the advantages and novel features of our invention will be readily apparent.

We desire it to be understood that we may make changes in the construction and in

the combination and arrangement of the several parts, provided that such changes fall within the scope of the appended claims.

What we claim as new is:—

- 5 1. An obstruction removing device of the character described comprising a headed cross bar, a hand lever pivotally secured to the cross bar, a ramming element, and means for moving said ramming element through
10 the medium of the lever.
2. In a device moving obstructions from sewers comprising an adjustable cross bar, a hand lever fulcrumed to the cross bar, a ramming element, a cam member receiving
15 the ramming element and a link connecting the cam member with the hand lever as and for the purpose specified.
3. A device for moving obstructions from sewers comprising an adjustable cross bar
20 engaging the side walls of the manhole of the sewer, a hand lever, a substantially U-shaped member, a ramming element received by the substantially U-shaped member for sliable movement therein, a grooved cam
25 member adapted to engage the ramming element, and a link pivotally connecting the

cam member to the hand lever as and for the purpose specified.

4. A device of the character described comprising an adjustable cross bar, a hand lever fulcrumed to said cross bar intermediate its ends, a link pivotally secured to the hand lever at one end and having its opposite end twisted upon right angles upon itself and bifurcated, a substantially V-shaped cam member received between the furcations of the bifurcated end, a substantially U-shaped member pivotally receiving the V-shaped cam member and being provided with an arcuate shaped bottom
30 with a channel shaped groove formed therein, a ramming element received between the bottom of the U-shaped element and within the groove of the V-shaped member and means for adjusting the U-shaped member with respect to the V-shaped member as and for the purpose specified.
35

In testimony whereof we affix our signatures.

ALLEN CROSS.
EVERT F. DUNCAN.
